Attorney

UNITED STATES PATENT OFFICE.

WALTER R. GREENLAND, OF LOS ANGELES, CALIFORNIA.

INK DISPENSER.

Application filed October 8, 1925. Serial No. 61,343.

My invention relates to fluid dispensing devices and particularly, although not necessarily, to devices for dispensing printer's ink.

It is a purpose of my invention to provide an ink dispenser of extremely simple, inexpensive and durable construction which effectively protects the ink against evaporation and consequent hardening when not in use, but which is manually operable to dispense ink in any quantity desired and in such manner that the ink is readily removable for application to a printing press.

I will describe only one form of ink dispenser embodying my invention, and will point out the novel features thereof in claim.

In the drawings

Figure 1 is a view showing in top plan one form of ink dispenser embodying my invention;

Figure 2 is a central vertical sectional view of the ink dispenser shown in Figure 1.

Referring specifically to the drawings, in which similar reference characters refer to similar parts in each of the views, my invention in its present embodiment comprises a vertical support 15, preferably hollow and formed of any suitable material, such as metal or the like. This support 15 is formed at its lower end with a flange 16 having openings 17 through which suitable fastening members can be extended for rigidly securing the support in upright position upon a table, printing press or the like. The upper end of the support is provided with a head 18 constituting a plunger, and exteriorly threaded to receive an internally threaded barrel 19. The upper end of the barrel is closed by means of a cap 20 having an interiorly threaded flange 21 engaging exterior threads on the barrel, whereby the cap is detachably associated with the barrel to permit the removal thereof for supplying ink to the barrel, as will be understood.

The upper or outer surface of the cap 20 is of concave form, as indicated at 22, so as to provide a cup portion to which ink from the barrel is supplied through a port 23 formed in the cap and centrally of the cup portion.

As shown in Figure 2, the upper side of the plunger 18 is provided with a thread cleaning member 24 in the form of a disk of felt or other suitable material of such diameter that its edge projects from the periphery of the plunger and into engagement

with the internal threads of the barrel 19 so that as the barrel is screwed downwardly upon the plunger the member will have wiping engagement with the threads to remove ink therefrom, thus preventing clogging of the threads to insure an easy and proper feeding of the barrel downwardly on the plunger. This member 24 is firmly clamped to the upper side of the plunger by means of a plate 25 secured to the plunger by screws 26.

In operation, the barrel 19, when in the uppermost position shown in Figure 2, can be filled with printer's ink by removal of the cap 20, and upon replacing the cap and rotating the barrel on the plunger the former will be brought downwardly to cause the plunger to move upwardly within the barrel and thereby place the ink under pressure. In this manner ink is ejected from the barrel through the port 23 and into the cup portion 22, the amount of ink ejected depending upon the downward adjustment of the barrel, as will be understood. From the cup portion 22 the ink ejected can be removed and applied to the printing press.

By virtue of the cup portion 22 the possibility of ink being accidentally discharged over the edges of the cap is precluded, and the ink which is not used is allowed to drain back into the barrel through the port 23.

Although I have herein shown and described only one form of ink dispenser embodying my invention, it is to be understood that various departures may be made therefrom without departing from the spirit of the invention, and within the spirit and scope of the appended claim.

I claim:

An ink dispenser comprising a vertical support having a flanged base through which fastening members are adapted to be extended for securing the support to a table, said support having its upper end flared to provide a flat topped cylindrical head, externally threaded, said head constituting a plunger, an open ended barrel threaded internally for threaded engagement with the head, said barrel threaded externally at its upper end, a cap having a depending flange threaded internally for threaded engagement with the upper end of the barrel, said cap having its upper surface concave to provide a cup portion and having a centrally disposed port through which ink in the barrel is adapted to be supplied to the cup

portion when the barrel is rotated to feed downwardly on the head, a thread cleaning member on the flat top of the head and comprising a disk of fibrous material of slightly larger diameter than that of the head, a clamping plate on the disk, and fastening members extending through the plate and

disk and into the head for securing the disk upon the latter with its peripheral edge projecting into the threads of the barrel so that when the barrel is rotated, the disk will have wiping engagement with the threads to prevent clogging of the latter by the ink. ¹⁰
